HINGE CONSTRUCTION

Carl C. Fish, Detroit, Mich., assignor to
Ferro Stamping Company

Application March 21, 1949, Serial No. 82,516

10 Claims. (Cl. 16—166)

1

This invention relates to hinges of the general type adapted to pivotally connect a swinging closure to a fixed support.

More particularly the present invention refers to a hinge construction which may be satisfactorily employed in connection with a vehicle body for the purpose of pivotally connecting the usual rear deck to the body structure forming the storage compartment. In accordance with this invention the hinge assembly is such as to enable supporting the same in an exceptionally small space to one side of the storage compartment, where it does not obstruct the latter. In fact the space occupied by the hinge assembly in any position of the latter is so small that it may be disregarded insofar as reducing the storage capacity of the compartment is concerned.

In many rear deck structures, as is also true with other types of installations, one edge of the deck or similar closure overlies a seat or seal on the adjacent edge of the supporting structure, and there is a tendency for the overlying edge of the closure to slide across or bite into the seal upon initial upward swinging movement of the closure. Also in some instances the overlying edge portion of the closure may scuff or rub against adjacent painted surfaces of the body structure and mar the same.

With the above in view it is a further object of this invention to incorporate a control feature in the hinge assembly which guides the closure throughout a path of travel such that the overlying edge or seal engaging lip moves bodily away from the seal in a direction generally normal to the latter upon initial upward swinging movement of the closure.

It is still another feature of this invention to control swinging movement of the closure so that the seal engaging lip also shifts a slight distance rearwardly and thereby minimizes any tendency for the front edge of the lip to scrape against the adjacent finished part of the body during initial swinging movement of the closure.

The foregoing as well as other objects will be made more apparent as this description proceeds, especially when considered in connection with the accompanying drawings, wherein:

Figure 1 is a side elevational view partly in section showing a hinge structure embodying the features of this invention and showing only a part of the spiral spring for the sake of clarity;

Figure 2 is a side elevational view partly in section showing the hinge structure in the position it assumes when the closure is swung to its open position;

2

Figure 3 is a sectional view taken substantially on the line 3—3 of Figure 1;

Figure 4 is a sectional view taken on the line 4—4 of Figure 1;

Figure 5 is a sectional view taken on the line 5—5 of Figure 1;

Figure 6 is a sectional view taken on the line 6—6 of Figure 2;

Figure 7 is a sectional view taken on the line 7—7 of Figure 2;

Figure 8 is a side elevational view partly in section of a modified form of hinge structure and showing the latter in the position it assumes when the closure is in its closed position;

Figure 9 is a side elevational view partly in section of the hinge structure shown in Figure 8, and illustrating the parts of the hinge in the relative positions they assume when the closure is swung to its open position;

Figure 10 is a sectional view taken on the line 10—10 of Figure 8;

Figure 11 is a sectional view taken on the line 11—11 of Figure 9; and

Figure 12 is a sectional view taken on the line 12—12 of Figure 9.

For the purpose of illustration the hinge structure embodying the features of this invention is shown in connection with a vehicle body for pivotally connecting the front edge of the usual rear deck closure to the body structure, although it will be understood as this description proceeds that the hinge may be employed for pivotally mounting other types of closures.

In general the numeral 10 designates fixed supporting means, or in the present instance, the part of a vehicle body which forms the top wall of the storage compartment at the rear of the body, and the numeral 11 indicates an opening which provides access to the interior of the storage compartment. The opening 11 is closed by a closure 12 having a lip or flange 13 extending forwardly from the front edge of the closure and adapted to set on a seal 14. The seal 14 extends along the rear edge of the supporting means 10 at the front side of the opening 11, and is carried by the supporting means. The closure 12 is pivoted to the supporting means by two hinge assemblies 15 located in the top of the storage compartment at opposite sides of the latter in positions where they are out of the way and do not obstruct the opening 11. The two hinge assemblies are identical in construction, and a description of one will suffice for both. Referring first to the embodiment of the invention shown in Figures 1 to 7 inclusive, it

will be noted that the hinge assembly comprises a bracket 16, an arm 17 and connecting linkage 18. The bracket 16 is in the form of a vertical plate located in the top of the storage compartment adjacent one side of the latter and positioned in advance of the front edge of the opening 11. The bracket or plate 16 is formed with a laterally extending attaching flange 19 at the front edge, and is formed with a similar flange 20 at the top edge. The flange 19 is suitably secured to a part 21 of the supporting means 10, and the flange 20 is secured to a part 22 of the fixed supporting means.

The arm 17 is secured at its rear end to the underside of the closure 12 by fastener elements 23, and projects forwardly beyond the front edge of the closure to a position at the outer side of the bracket 16. The front or free end portion of the arm 17 is curved upwardly slightly, and a follower 25 is secured to the extremity of the upwardly curved portion. As shown in Figure 3 of the drawings, the follower 25 slidably engages in an elongated slot 26 formed in the plate or bracket 16. The slot 26 extends forwardly in a straight line from a point located directly below the front side of the opening 11 and is of sufficient length to enable swinging movement of the closure from the closed position thereof shown in Figure 1 of the drawings to the open position shown in Figure 2 of the drawings.

The linkage 18 includes a link 27 having the rear end pivotally supported on the outer side of the arm 17 at a point directly below the flange 13 on the closure 12. As shown in Figure 5 of the drawings, a generally U-shaped bracket 28 is secured to the outer side of the arm 17, and the rear end of the link is pivoted to the base of the bracket 28 by a pin 29. The front end of the link 27 also extends along the outer side of the plate or bracket 16, and is offset laterally inwardly in the manner shown in Figure 7 of the drawings to assume a position immediately adjacent the plate 16. The front end of the link 27 is pivotally connected to a shouldered follower pin 28', and the latter slidably engages in a slot 29' formed in the plate 16 below the slot 26.

The linkage 18 also includes a link 30 having the lower end pivotally connected to the link 27 intermediate the ends of the latter by a pin 31. The upper end of the link 30 is pivoted to a bracket 32 by means of a pin 33, and the bracket 32 is secured to the flange 20 of the plate 16 at a point above the slot 26 adjacent the front end of the latter.

The above arrangement is such that when the closure 12 is in its closed position, the follower 25 at the front end of the arm 17 is located at the front end of the slot 26, and the pin 28' on the front end of the link 27 is located at the front end of the slot 29'. Also in the above position the link 30 assumes a substantially vertical position, so that as the rear end of the closure is raised, the links cooperate to swing the closure to the position thereof shown in Figure 2 of the drawings. In this connection it is pointed out that the slot 29' is arcuate in shape, and coacts with the front end of the link 27 to guide swinging movement of the closure 12. The contour of the slot 29' is such that the flange 13 at the front edge of the closure 12 moves upwardly along the path indicated by the dot and dash line 35 in Figure 2 of the drawings. This path of travel is such that the flange 13 is moved bodily away from the seal 14 in a direction substantially normal to the latter, so that there is no tendency for the flange 13 to scuff

or dig into the seal during initial upward movement of the closure. In fact it will be observed from the path 35 shown in Figure 2 of the drawings that the flange also moves rearwardly slightly during its upward travel, and this is desirable in that it prevents any possibility of the flange contacting the adjacent body structure and chipping the paint from the latter. Attention is also called to the fact that as the closure 12 is swung upwardly, the pin or follower 25 on the front end of the arm 17 moves rearwardly along the slot 26 to a position directly below the front side of the opening 11. This arrangement enables obtaining the desired movement of the closure without the necessity of employing a deep throated "gooseneck" type arm, and this feature is important in that it enables reducing the overall size of the hinge structure.

Supported on the inner side of the plate 16 is a pair of links 36 and 37. The adjacent ends of the links are pivotally connected together by a stud 38, and the outer ends of the links are respectively pivotally connected to the supporting means 10 and the front end of the link 27. In detail the outer end of the link 36 is pivoted to the plate 16 by a pin 39, and the outer end of the link 37 is pivoted to the follower pin 28' previously described as carried by the front end of the link 27. The link 36 has a rearward extension 40, and the latter is formed with an inwardly extending lug 41. As shown in Figure 6 of the drawings, a spiral type spring 42 is mounted on the stud 38, and the latter is secured to the inner end of the link 37. As shown in Figure 6 of the drawing the inner end 43 of the spring is anchored in a slot formed in the head of the stud 38, and the outer end 44 is looped around the bottom of the lug 41. The arrangement is such that the spring 42 applies an upward thrust on the extension 40 of the link 36 and assists movement of the closure to its open position. Inasmuch as the outer end of the link 27 is connected to the follower 28', it will be noted that when the closure is in its closed position, the outer end of the link, or in other words the pin 28', lies directly below the pin 39. Thus the spring force applied to the extension 40 of the link 36 tending to open the closure is at a minimum when the closure is in its closed position, and progressively increases as the closure is raised. In other words one end of the spring is attached to stud 38 which in turn is secured to link 37 so that as the lid is raised, stud 38 revolves counter-clockwise (Figure 2) thereby in effect winding the spring and increasing its upward force on lug 41.

The embodiment of the invention shown in Figures 8 to 12 inclusive is similar to the construction described above, and corresponding parts are designated by the same reference numerals. In the embodiment shown in Figures 8 to 12 inclusive, the closure 12 is guided throughout its swinging movement in a path 45, corresponding generally to the path 35, by a link 46 similar to the link 30 of the construction described above. The upper end of the link 46 is pivoted by a pin 47 to the plate 16 at a point 47 spaced forwardly from the pin 33, and the lower end of the link 46 is pivoted to the front end of the link 27 by a pin 48. The arrangement is such that when the closure 12 is swung upwardly from its closed position shown in Figure 8 to the open position shown in Figure 9, the flange 13 moves along the path 45. As stated above this path is similar to the path 35 described in connection with the first embodiment of this invention, and the same results are obtained.

As shown partly in Figure 11 of the drawings, the rear end of the link 27 is pivoted to the bracket 28 by a stud 49, and a spiral type spring 50 is mounted on the stud 49. The inner end of the spring is anchored on the stud 49 in the usual manner, and the outer end of the spring is looped beneath a pin 57 secured to the link 27 adjacent the stud 49.

It follows from the above that the location of the spring 50 in relation to the links is such that when the closure 12 is in its closed position shown in Figure 8 of the drawings, the spring is under substantially maximum tension, and the line of force applied to the link 27 by the outer end of the spring is such that the spring acts to hold the closure 12 in its closed position. However, upon initial upward movement of the closure, the spring is shifted rearwardly and acts to assist in raising the closure to its fully opened position shown in Figure 9 of the drawings.

With the above noted exceptions and with the exception of the specific shape of some of the parts, the construction shown in Figures 8 to 12 inclusive is similar to the arrangement previously described in connection with Figures 1 to 7 inclusive. Both constructions are of a nature to enable readily installing the same in positions in the storage compartment where they do not interfere with or obstruct the opening 11. Thus baggage or other articles may be readily inserted through the opening 11 into the storage compartment. It will also be noted that both types of hinge assemblies are very compact, and are adapted to be positioned at the top of the storage compartment forwardly of the front edge of the opening so that the space in the storage compartment occupied by the hinge assemblies is negligible. It will further be noted that the linkage embodied in the hinge assemblies shown in Figures 8 to 12 inclusive is supported at the outer side of the plate 16 with the result that the plate acts as a shield to prevent the linkage from interfering with baggage or the like in the storage compartment. This is also true of the first embodiment of the invention with the exception of the two small links 26 and 37.

What I claim as my invention is:

1. A hinge structure for a swinging closure, comprising a fixed mounting bracket, an arm adapted to be fixed at one end to the closure, a combined slidable and pivotal connection between the other end of the arm and mounting bracket enabling sliding movement of the arm relative to the bracket during swinging movement of the closure, a first link having one end portion pivoted to said arm, a second link pivotally connecting the other end portion of the first link to the bracket, and a combined slidable and pivotal connection between the first link and bracket for guiding swinging movement of the arm along a predetermined path of travel.

2. A hinge structure for a swinging closure, comprising a fixed mounting bracket, an arm adapted to be fixed at one end to the closure, a combined slidable and pivotal connection between the other end of the arm and bracket enabling sliding movement of the arm relative to the bracket during swinging movement of the closure, a first link having one end pivoted to said arm, a second link having one end pivoted to the bracket and having the other end pivoted to the first link intermediate the ends thereof, and a third link having one end pivoted to the bracket adjacent the pivotal connection of the second link to the bracket and having the other end pivoted

to the first link adjacent the other end of the latter.

3. A hinge structure for a swinging closure, comprising a fixed mounting bracket, an arm fixed at one end to the closure, a combined slidable and pivotal connection between the free end of the arm and bracket enabling sliding movement of the arm relative to the bracket during swinging movement of the closure, a first link having one end pivoted to the arm intermediate the ends of the latter, a second link having one end pivoted to the bracket and having the other end pivoted to the first link intermediate the ends thereof, a combined slidable and pivotal connection between the other end of the first link and said mounting bracket for guiding swinging movement of the closure, a pair of links having the adjacent ends pivotally connected and having the other ends respectively pivotally connected to the bracket and the other end of the first link, and spring means associated with the pair of links for assisting swinging movement of the closure in one direction.

4. A hinge structure for a swinging closure having a portion at one edge adapted to rest on a seating part, comprising a fixed mounting bracket, an arm adapted to be fixed at one end to the closure, a combined slidable and pivotal connection between the other end of the arm and bracket at a point spaced below the seating part enabling sliding movement of the arm relative to the bracket, whereby the closure is permitted to move bodily away from the seating part upon swinging movement of the closure toward its open position, a first link having one end portion pivoted to said arm, a second link pivotally connecting the other end portion of the first link to the bracket, and a combined slidable and pivotal connection between the first link and bracket for guiding swinging movement of the arm along a pre-determined path of travel.

5. A hinge assembly for a swinging closure having a portion at one edge adapted to rest on a seating part, comprising a fixed mounting bracket having a part adapted to be positioned below the seating part, an arm adapted to be fixed at one end to the closure, a combined slidable and pivotal connection between the other end of the arm and said bracket part at a point spaced below the seating part enabling sliding movement of the arm relative to the bracket, whereby the closure is permitted to move bodily away from the seating part upon swinging movement of the closure toward open position, a first link having one end portion pivoted to said arm, a second link pivotally connecting the other end portion of the first link to the bracket, and a follower on the other end portion of the first link spaced from the pivotal connection of the second link to the first link and slidably engageable in an elongated slot in the bracket, said slot being shaped to guide swinging movement of the arm along a pre-determined path of travel.

6. A hinge structure for a swinging closure having an edge portion adapted to seat on a fixed supporting part, comprising a fixed mounting bracket adapted to be positioned below the supporting part and having an elongated slot therein, an arm adapted to be fixed at one end to the closure, a follower moveable along the slot and connected to the other end portion of said arm, enabling sliding movement of the arm relative to the bracket, whereby the closure is

permitted to move bodily away from the supporting part upon initial swinging movement of the closure toward open position, a first link having one end portion pivoted to the arm, a second link having one end pivoted to the first link intermediate the ends thereof and having the other end pivoted to the bracket at a point above the slot, and a combined slidable and pivotal connection between the other end portion of the first link and the bracket for guiding swinging movement of the arm along a pre-determined path of travel.

7. A hinge assembly for a swinging closure having a portion at one edge adapted to rest on a seating part, comprising a fixed mounting bracket having a portion adapted to be positioned below the seating part and having a first elongated slot in said portion, an arm adapted to be fixed at one end to the closure, a follower carried by the free end of the arm and slidably engageable in the slot enabling sliding movement of the arm relative to the bracket, whereby the closure is permitted to move bodily away from the seating part upon initial swinging movement of the closure toward its open position, a first link having one end pivoted to the arm intermediate the ends of the latter, a second link pivoted to the bracket above the slot and having the opposite end pivotally connected to the first link intermediate the ends of the latter, and a follower on the other end of the first link slidably engageable in a second elongated slot formed in said portion of the bracket below the first slot, said second slot being shaped to guide swinging movement of the arm along a pre-determined path of travel.

8. A hinge assembly for a swinging closure having a portion at one edge adapted to rest on a seating part, comprising a fixed mounting bracket having a portion adapted to be positioned below the seating part and having an elongated slot in said portion, an arm adapted to be fixed at one end to the closure and having the other end adapted to project below the seating part, a follower slidably supported in the slot and connected to the free end of the arm enabling sliding movement of the latter relative to the bracket, whereby the closure is permitted to move bodily away from the seating part upon initial swinging movement of the closure to open position, a first link having one end pivotally connected to the arm intermediate the ends thereof, a second link having one end pivotally connected to the bracket and having the other end pivotally connected to the first link intermediate the ends thereof, a combined slidable and pivotal connection between the other end of the first link and the bracket for guiding swinging movement of the arm along a pre-determined path of travel, a 60 pair of links having their adjacent ends pivotally connected together and having their other ends respectively pivotally connected to the bracket and to the said other end of the

first link, and spring means associated with said pair of links for assisting swinging movement of the closure in one direction.

9. A hinge assembly for a swinging closure having a portion at one edge adapted to rest on a seating part, comprising a fixed mounting bracket adapted to be positioned below the seating part and having a first elongated slot therein, an arm adapted to be fixed at one end 10 to the closure and having the other end adapted to project below the seating part, a follower slidably supported in the slot and connected to the free end of the arm enabling sliding movement of the arm relative to the bracket, whereby 15 the closure is permitted to move bodily away from the seating part upon movement of the closure toward open position, a first link having one end pivotally connected to the arm intermediate the ends thereof, a second link having one end pivotally connected to the bracket and having the other end pivotally connected to the first link intermediate the ends thereof, a follower on the other end of the first link slidably engageable in a second elongated slot in said 20 portion of the bracket for guiding swinging movement of the arm along a pre-determined path of travel, a pair of links having their adjacent ends pivotally connected together and having their other ends respectively pivotally connected 25 to the bracket and said other end of the first link, and spring means associated with said pair of links for assisting swinging movement of the closure in one direction.

10. A hinge assembly for a swinging closure, comprising a mounting bracket having an elongated slot therein, an arm adapted to be fixed at one end to the closure, a follower on the other end of the arm slidably engageable in the slot, a first link having one end portion pivoted to the arm intermediate the ends of the latter, a second link having one end pivotally connected to the bracket at a point above said slot and having the other end pivotally connected to the first link intermediate the ends of the latter, 45 and a third link having one end pivotally connected to the bracket at a point spaced from the pivotal connection of the second link to said bracket and having the other end pivotally connected to the said other end of the first link at a point spaced from the pivotal connection of the second link to the first link.
